United States Patent Office

Des. 184,817
Patented Apr. 7, 1959

184,817

JEWELRY CLOSING OR THE LIKE

Adolph Katz, Providence, R.I., assignor to Coro, Inc.,
New York, N.Y., a corporation of New York

Application July 17, 1958, Serial No. 51,824

Term of patent 7 years

(Cl. D45—1)

Fig. 1

Fig. 2

Fig. 1 is a plan view of a jewelry closing or the like showing my new design.

Fig. 2 is an edge view thereof.

I claim:

The ornamental design for a jewelry closing or the like, substantially as shown.
